(57) **CLAIM**

The ornamental design for a base station for a cordless telephone, as shown and described.

DESCRIPTION

FIG. 1 is a front elevational view of a base station for a cordless telephone showing our new design;

FIG. 2 is a rear elevational view thereof;

FIG. 3 is a top plan view thereof;

FIG. 4 is a bottom plan view thereof;

FIG. 5 is a right side view thereof;

FIG. 6 is a left side view thereof; and,

FIG. 7 is a perspective view thereof.

The broken lines in FIGS. 2 and 4 that show the outermost periphery of non-claimed features represent the boundaries of the claimed design while all other broken lines are directed to environment and are for illustrative purposes only: the broken lines form no part of the claimed invention.
